UNITED STATES PATENT OFFICE

PAUL F. W. C. KRIPPENDORE, OF LYNN, MASSACHUSETTS, ASSIGNOR TO FITZ-EMPIRE
DOUBLE PIVOT LAST COMPANY, OF AUBURN, MAINE, A CORPORATION OF MAINE

SHOE AND INSOLE

Application filed January 23, 1926. Serial No. 83,376.

This invention relates to improvements in shoes and insoles. In the embodiment selected for illustration the invention is shown as used in the manufacture of shoes of the 5 welt type. It is to be understood, however, that the invention is equally applicable to the manufacture of shoes of other types.

An object of this invention is to produce a shoe which, while retaining all the style and 10 shapeliness characteristic of good shoemaking, will at the same time so meet the natural requirements of a normal human foot that it will not only be extremely comfortable to wear but will also tend to prevent development 15 of any abnormalities, such for example as falling arches, and where such deformities have occurred, will tend to correct them.

From a study of impressions of the normal 20 human foot in plastic material and from considerations of the anatomy of the foot I have discovered that a support for the forepart of the foot, such as the inside of a shoe, should be flat for a considerable area, this area being roughly triangular with the base of the triangle 25 corresponding substantially to the ball line of a last which may be defined as a line extending transversely of the last a short distance (say one half inch) at the rear of the line joining the anterior ends of the first and 30 fifth metatarsal bones. The apex of the triangle lies between the phalanges of the great toe and the second toe. This flat triangular area should lie in a plane substantially parallel to the tread plane of the shoe, that is, 35 for example, the plane of the tread face of the heel extended forwardly. The forepart area outside of this approximately triangular area should extend upwardly and outwardly to a degree approximating the usual spring of a 40 last.

Accordingly, in an important aspect, the present invention consists in a shoe the foot-engaging surface of the forepart of the insole of which has a substantially flat, triangular area lying parallel to the tread plane 45 of the shoe. To this end, the insole of the illustrated shoe is formed with a substantially flat portion in the shape of a triangle the base of which is substantially at the ball 50 line of the last and the apex of which lies

between the great and second toes, the forepart area outside of the triangular area from the ball line forward being directed upwardly and outwardly to an extent substantially approximating the usual spring of a last. In 55 this construction the surface below the anterior metatarsal arch is flat and hence offers no resistance to the natural flattening of the arch as the foot is bent in walking and at the same time prevents the flattening movement 60 from going too far as would be the case if this surface were transversely concave. Moreover, since the ball line of the shoe at which the bend of the toes should occur in walking is perfectly straight, the maximum flexibility 65 of the sole at this line is afforded, for obviously any transverse curvature of the sole along this line would tend to stiffen the sole.

It is observable that when the foot is pressed 70 lightly on a flat surface the ends of the toes are slightly raised from that surface; hence, by the structure described comprising a flat, triangular area with an upwardly and outwardly extending margin, a support for the toes in their natural position is afforded. 75 This construction adds greatly to the comfort of the shoe and tends to prevent friction between the toes and the interior of the shoe during the act of walking.

One of the principal bearing points of the 80 foot is at the head of the fifth metatarsal bone where it joins the cuboid bone. The principal nerves and blood vessels of the foot run along near the outer side of the foot just inside of the bearing point referred to. In 85 fact, most of these nerves and blood vessels will be found to lie approximately above a line drawn from about the center of the breast line to the outer end of the ball line of the shoe. Hence, it is desirable to avoid any 90 pressure upon the bottom of the foot in the region of this line which would tend to interfere with the nerve control, blood circulating or muscular action.

In view of the foregoing and in accordance 95 with another feature of the present invention the illustrated shoe is provided with a shank portion which extends in a straight line from about the center of the breast line to a point adjacent to the outer end of the ball line. By 100

thus dispensing with any longitudinal arch along this line, pressure such as would interfere with free action of the tendons, impede circulation in the blood vessels, or impair the function of the nerves, is avoided.

At each side of the above-mentioned straight line it is desirable that the shank portion of the sole have a pronounced transverse curvature, especially at the inner side of the shank where it is important that the insole be caused to extend well into the hollow or longitudinal arch on the inner side of the foot so as to conform to the anatomical structure of the foot. This formation not only preserves the natural arch of the foot and adds much to the appearance of the shoe, but also affords a support for the shank of the foot against lateral movement in either direction so that the tendency of the wearer to run the shoe over on either side is obviated. It is desirable also to provide a pronounced pocket for the ball of the heel. This not only contributes to the comfort of the wearer by keeping the cushion under the heel bone where it belongs, but also prevents any tendency of the shoe to run over at the counter portion. To obtain these results the insole of the illustrated shoe is not cut away on the inner side but has practically the full contour except that, advantageously, a slight indentation or notch may be formed at the inner end of the ball line to locate the inner end of the ball line and facilitate bending of the sole. The illustrated insole is practically straight, that is, nearly bilaterally symmetrical with respect to its longitudinal axis. Hence, when it is applied to a crooked last the longitudinal median line of the rear portion must be deflected laterally with respect to the longitudinal median line of the forepart, so that the material of the insole on the inner side of the shank is caused to buckle and tend to enter the arch of the shank on that side of the last.

In order to maintain, during the wear of the shoe, the described transverse curvature and arched condition of the insole and outsole, after the shoe is completed to the point of applying the heel, the illustrated shoe is provided with rows of fastenings extending lengthwise of the shank, the fastenings extending through and through the insole and outsole. These lines of fastenings act effectively to maintain the transverse curvature of the shank throughout the wear of the shoe. Instead of these fastenings I may unite the insole and outsole from the ball to the heel breast in their entirety by other suitable means.

In the drawings,—

Fig. 1 is a perspective view, partly in section, showing the interior surfaces of the insole of a shoe embodying the present invention, the shoe being partly in section;

Fig. 2 is a sectional detail of the shank portion of the shoe;

Fig. 3 is a view similar to Fig. 2 taken at the forepart;

Fig. 4 is a side elevation of a last used in making the shoe;

Fig. 5 is a perspective view showing the bottom surface of the last illustrated in Fig. 2;

Fig. 6 is a view illustrating the insole 75 blanks employed and the manner in which they are cut from the stock; and

Fig. 7 is a view of the plantar surface of the bones of a normal human foot.

Referring to Figs. 4 and 5, which represent a last 10, it will be seen that there is upon the forepart of the last bottom a flat area bounded by a line having a curved part 12 and a straight part 14. In Fig. 5 a heavy broken line A, B, C, D has been drawn upon the last bottom to assist in describing various characteristics of the last. The line B—C represents substantially the ball line or, as shown in Fig. 7 the line joining the centers of the anterior ends of the first and fifth metatarsal bones. The line C—D is equal in length to B—C, and the angle BCD is a right angle. It is found that the line C—D represents very approximately the direction of the first phalanges, that is, the direction of the great toe. It will be noted that the area enclosed by the triangle BCD approximates the area enclosed by the line 12, 14, the shape of the triangle having been rounded and softened by the curved line 12 and the straight portion 14 corresponding substantially to the ball line of the last. The line 12 defines a shape forward of the ball line approximating the shape of the forepart of the last, and between the line 12 and the periphery 16 of the forepart of the last is a crescent-shaped area 18 which slopes outwardly and upwardly from the line 12. This is best seen from Fig. 4 where the last is represented as having the flat surface of its forepart pressed upon a flat tread surface F—G. It will be seen that the peripheral line 16 extends from the ball line forwardly and upwardly in a gentle curve representing approximately the spring of a usual last. This figure also indicates the vertical curvature of the crescent-shaped surface 18. It will be noted also that the rear portion of the last is raised from the surface F—G a distance representing the height of the heel required for the last. The flat area of the forepart bounded by the line 12, 14 represents the area of the forepart of the foot which presses upon a flat surface in the act of standing. The crescent-shaped area has the described outward and upward inclination for the purpose of supporting the toes in what is their natural position, that is, slightly elevated from the flat tread surface.

The line B—C represents approximately the line on which the forepart of the foot bends and the line 14 parallel to it represents the ball line of the last and approximately the line along which the insole of the shoe has to bend in the act of walking. The line along which the insole has to bend is therefore straight and maximum flexibility of the insole is assured since there is no transverse curvature of the sole at the ball line to interfere with its bending. This flat surface along the ball line B—C permits the anterior transverse arch of the foot to flatten out as it naturally does when the toes are bent and pressure is applied to the ground in walking but it prevents this arch from bending too far as is the case when the surface pressed on is concave as it frequently is instead of flat.

The line A—B extends from about the center of the breast line represented by the forward edge of a heel plate 20, secured to the heel-seat of the last, to the outer end B of the ball line and is a straight line, the surface of the shank portion of the last having no vertical curvature along this line.

It has been found that many of the important blood vessels, nerves and tendons of the foot lie adjacent to the vertical plane of the line A—B, and that any upward arch of the shank portion of the shoe along this line tends to produce pressure upon these blood vessels, nerves and tendons and to interfere with circulation, sensation and normal action of the foot muscles. For example, the tendon of a muscle on the inner side of the leg, called flexor longus digitorum, passes downwardly and then horizontally through a groove in the astragalus bone shown at 21 (Fig. 7) and thence in a direction toward the outer end of the ball line. This tendon finally branches into four parts, one of which is attached to the first phalange of each of the four smaller toes. The tendon is drawn by the muscle through the groove 21 as through a pulley and the portion of the tendon running along the bottom of the foot tends to assume a straight line parallel to the line A—B. It is also especially to be noted that the groove 22 in the plantar surface of the cuboid bone, through which the tendon of the leg muscle peroneus longus passes to its point of attachment at 24 to the posterior portion of the first metatarsal bone, lies over this line. Since the line A—B is a straight line while the foot has a slight natural longitudinal arch above this line, objectionable pressure upon these tendons is avoided. The normal action of the muscle peroneus longus helps in maintaining the posterior transverse arch of the foot and hence my construction, which prevents pressure upon and interference with this tendon and hence with its muscle, avoids a frequent cause of foot trouble.

The heel-seat surface of a last represented by the plate 20 is made very convex so that a pronounced cup will be formed in the insole to receive the heel portion of the foot and prevent lateral movement of the foot with respect to the heel, thus avoiding running over of the heel.

A last having the characteristics described having been made, an insole 26 is prepared. The insole, as indicated in Fig. 6, is made straighter than the last; in fact, the insole may generally be substantially bilaterally symmetrical with respect to its longitudinal median line. Preferably, however, a notch 28 is made at the inner end of the ball line. The insoles are preferably cut by reversing the pattern or die end for end for each cutting and placing it as close as possible to the previously cut edge. The result is that there is practically no loss of material except at the ends of the insoles. The material between the inner end of the ball line and breast line, as indicated by dotted lines in Fig. 6, which is usually cut away and wasted, is, by my method, left in the insole to fulfill a useful purpose as will later appear.

The forepart of the insole is channeled, as is usual for welt work, the shank portion being left unchanneled. The insoles are tempered and one of them is placed on the bottom of the last with its forepart coincident with that of the last. Since the insole is straighter than the last it will be necessary to swing the rear portion of the insole toward the inner side of the last to bring the heel portions over each other, and this act will cause the material between the inner end of the ball line and the breast line to buckle toward the shank portion of the last.

The last and insole are next placed in a press with the insole resting on a block of rubber or other yielding material. Sufficient pressure is then applied to the last to cause the insole to conform perfectly to the bottom of the last and permanently to assume the shape of the last bottom.

The notch 28 is at the junction between the flat forepart area and the concave shank area and prevents any stiffness due to the curling up of the inner margin of the shank from being carried forward from the ball line and hence interfering with the flexibility of the sole. By cutting out the insole as described the material between the heel and ball on the inner side of the insole, which is usually wasted, is saved and utilized to form, at no extra expense, an adequate shank support for the foot, the only material wasted being at the rounded ends of the pattern.

The upper is then placed over the insole and last and the shoe lasted about the shank and forepart in the usual manner by drawing the margin of the upper over upon the bottom of the insole and securing it temporarily by lasting tacks driven through the upper and insole into the wood of the last bottom. At the shank the lasting may be done in any usual

130

manner, for example, the insole and upper may be coated with cement so that when the cement has set and the temporary tacks are withdrawn the upper will be held permanently in lasted position. A welt is attached with the upper to the lip or rib of the insole about the forepart, and the heel-seat portion of the upper is lasted in and secured by tacks clinched upon the heel plate 20. The temporary lasting tacks are now withdrawn and the upper trimmed at the forepart and, if necessary, filling material may be introduced. It is found, however, that, by reason of the upward and outward curvature of the area 16 about the periphery of the last and insole, a space is provided for the accommodation of the inseam so that little or no filling is necessary, this construction being illustrated in Fig. 3. At the toe a small amount of filling 20 may be required in the channel to fill it up even with the inseam. An outsole 29 is next applied to the shoe and is preferably shaped to the shoe bottom in a manner similar to that employed for shaping the insole. The forepart of the outsole is next attached to the welt by an outsole stitching machine in the usual manner. The last is now withdrawn from the shoe and through-and-through seams 30, 32 sewn along the margin of the insole to secure the insole, upper and outsole together. In addition, two other seams 34, 36 are sewn through the two soles for the purpose of causing the transverse curvature of the shank portions of the sole to be maintained. Instead of the seams 34, 36, other means of fastening may be employed, the purpose being to prevent relative movement of the insole and outsole or the bulging of one outwardly with respect to the other such as would be necessary if this transverse curvature of the insole were flattened out while the soles were held by the seams 30, 32.

The novel features exemplified by the last herein illustrated have not been claimed herein since they are claimed in a divisional application, Serial No. 384,315, filed August 8, 1929.

Having thus described my invention, what I claim as new and desire to secure by Letters 50 Patent of the United States is:

1. A shoe having an insole the forepart of which has a flat area extending from a line at the rear of the ball line of the foot and diminishing in width transversely of the shoe 55 to a point between the great toe and the second toe, the surface of the insole outside of and forward of said area extending upwardly and outwardly to afford a bearing surface for the outer portions of the toes.
2. A shoe having an insole the forepart of which has a flat, triangular area extending from the ball line at the rear of the enlargements at the forward ends of the first and fifth metatarsal bones to a point between 60 the great toe and the second toe, said trian-

gular area being sufficient to afford support for the portion of the forepart of the foot first touching the ground including substantially the area covered by the inner phalanges, the toe portion of the insole outside the said flat area being curved upwardly and outwardly from the periphery of said flat area to the periphery of the shoe bottom to support the outer phalanges in their natural position. 70

3. A shoe having an insole shaped to extend in a straight line from the mid portion of the breast line to the outer end of the ball line for the purpose of preventing pressure on the blood vessels, nerves and tendons extending along near the surface of this portion of the 75 foot. 80

4. A shoe having an insole and outsole shaped to extend in a straight line from the mid portion of the breast line to the outer end of the ball line for the purpose of preventing pressure on the blood vessels, nerves and tendons extending along near the surface of this portion of the 85 foot. 90

5. A shoe having an insole and outsole shaped to form a concave trough for the shank portion of the foot, and more than two longitudinally extending rows of fastenings extending through and through the shank portions of both soles to maintain the interior concavity and exterior convexity of the shank 95 portion of the sole. 95

6. A shoe having an insole and outsole shaped to form a concave trough for the shank portion of the foot, and means for maintaining the interior concavity and exterior convexity of the shank portion of the sole. 100

7. A shoe having an insole and outsole shaped to extend in a straight line from approximately the mid portion of the breast line to the outer end of the ball line and shaped transversely of that line to form a concave trough for the shank portion of the foot, and means for maintaining the interior of concavity and exterior convexity of the shank 105 portion of the sole. 110

8. A shoe having a shank portion formed by inner and outer soles, said shank portions being transversely curved to form a concave trough lengthwise of the foot, the bottom of said trough being straight and extending from the center of the breast line to the outer end of the ball line, and means for stiffening the soles to maintain the transverse curvature. 115

9. A shoe having a shank portion formed by inner and outer soles, said shank portion being transversely curved to form a concave trough lengthwise of the foot, and through-and-through fastenings extending in lines lengthwise of the shank to stiffen the soles 120 against reduction of the transverse curvature. 125

10. An insole for shoes having excess material on its inner side the extent of which outwardly of the insole is substantially defined by a straight line connecting the inner 130

ends of the ball line and the breast line, said excess material being molded into a shape to enter the longitudinal arch on the inner side of the foot, said insole having in its edge a sharp notch the apex of which is located adjacent to the inner end of the ball line to prevent the stiffening effect due to said molding from extending beyond the ball line and the ball line being straight from side to side to afford maximum flexibility of the insole at the ball line.

11. An insole for shoes having a flat and substantially triangular area on its forepart with an upwardly and outwardly extending margin outside of said area.

12. An insole for shoes having its inner face straight along the line from the center of the breast line to the outer end of the ball line, the remaining portions of the shank 20 being transversely concave.

13. An insole for shoes having its inner surface straight along a line from approximately the center of the breast to the outer end of the ball line and having a substantially 25 flat area from the ball line forward at the central portion of the forepart.

14. An insole for shoes having its inner face straight along the line from approximately the center of the breast line to the 30 outer end of the ball line, the remaining portions of the shank being transversely concave and the heel-seat portion being deeply cupped.

15. An insole for shoes having in the inner 35 face of the shank portion a groove or trough the bottom of which extends in a straight line from the center of the breast line to the outer end of the ball line, said groove being for the purpose of avoiding excessive pressure on the 40 nerves of the foot, on the external plantar arteries supplying the plantar surface of the foot, and preventing interference with the action of the tendons of certain muscles, particularly that of peroneus longus.

16. An insole for shoes having in the inner face of the shank portion a groove or trough the bottom of which extends in a straight line from the center of the breast line to the outer end of the ball line, said groove 50 being for the purpose of avoiding excess pressure on the nerves of the foot on the external plantar arteries supplying the plantar surface of the foot and preventing interference with the tendons of the peroneus longus and flexor longus digitorum muscles.

In testimony whereof I have signed my name to this specification.

PAUL F. W. C. KRIPPENDORF.
